UNITED STATES PATENT OFFICE.

CHARLES T. WESTLAKE, OF ST. LOUIS, MISSOURI, ASSIGNOR TO FLORY CARRY IRON COMPANY, OF ST. LOUIS, MISSOURI, A CORPORATION OF DELAWARE.

DRAW-BAR CARRY-IRON.

1,239,651.

Specification of Letters Patent. Patented Sept. 11, 1917.

Application filed September 30, 1915. Serial No. 53,390.

To all whom it may concern:

Be it known that I, CHARLES T. WESTLAKE, a citizen of the United States, residing at the city of St. Louis, State of Missouri, have invented a certain new and useful Improvement in Draw-Bar Carry-Irons, of which the following is a full, clear, and exact description, such as will enable others skilled in the art to which it appertains to make and use the same, reference being had to the accompanying drawings, forming part of this specification.

This invention relates to certain new and useful improvements in draw bar carry iron for railway cars, and specifically is an improvement on the form of carry iron disclosed in my U. S. Letters Patent No. 1,125,420 granted January 19, 1915.

In the said Letters Patent is disclosed a carry iron in the nature of a roller provided with eccentric trunnions at its ends which are mounted to roll on suitable supports, thus providing a roller support for the draw bar. The eccentric disposal of the trunnions or axis of the carry iron enables it to be disposed so that it will support the draw bar at different elevations, depending upon whether or not the carry iron is disposed with its maximum radius above or below the bearing point of the trunnions upon the support.

My present invention has for its objects the provision of means which will insure the rolling operation of the carry iron under the buffing and pulling movements of the draw bar, which will facilitate the centering of the carry iron on its support, and which will prevent the complete overturning of the roller.

Other objects will be obvious or pointed out hereinafter.

In the accompanying drawings in which one embodiment of my invention is illustrated—

Figure 1 represents a front elevation of a striking plate and carry iron of my improved construction, the draw bar being shown in section;

Fig. 2 is a transverse section through the carry iron and its support substantially on line 2—2 of Fig. 1;

Fig. 3 is a view similar to Fig. 2, except

that the carry iron is shown in its inverted or high position;

Fig. 4 is a perspective of the carry iron or roller; and

Fig. 5 is a perspective detail of one of the supports.

Referring to the drawings in detail, it will be understood that the numeral 1 indicates a casting shaped to form a striking plate and adapted for attachment to the end sill or dead block of a car. This striking plate is formed with depending supports 2 having inwardly presented horizontal ledges 4 adjacent their lower extremities. These supports 2 are apertured for the reception of a bolt 8, which, as is readily apparent from the drawing, and as will be understood from my patent above referred to, is adapted to retain the carry iron or roller in position.

This carry iron comprises a main body portion 5 having circular lugs or trunnions 6 at its ends. The roller has one curved bearing face 5^a which may be concentric with the trunnions, and a high bearing face 5^b which is on a considerably greater radius so that it is further spaced apart from the axis of the trunnions than is the low bearing face 5^a. As illustrated, these bearing faces are disposed substantially opposite each other. The roller is formed with a longitudinal interior channel 7 of considerable width.

Formed on the supporting ledges 4 are upstanding lugs 9, and provided in the trunnions 6 are apertures 10 of suitable size and shape to receive the lugs 9 when the trunnions are resting on the supporting ledges 9.

In each of the trunnions one of these apertures 10 is disposed diametrically opposite to the low bearing face 5^a, and another is disposed diametrically opposite to the high bearing face 5^b. When the roller is placed in operative position, the trunnions rest upon the supporting ledges 4, so that the lugs 9 register in the lower apertures 10. The bolt or pin 8 is then inserted through the apertures in the supporting members 2 and the central channel 7 of the roller. If it is desired to support the carry iron in the lower position, the low bearing face 5^a is disposed uppermost, while if it

is desired to support the draw bar in the higher position, the higher bearing face 5^b is disposed uppermost. This feature is described in detail in my former patent above mentioned.

5 The draw bar *a* is supported on the upper face of the carry iron. Whenever there is a longitudinal movement of the draw bar, due to pulling or buffing action, the carry iron 5 will act as a roller between the draw bar and the supports, thus permitting the movement of the draw bar with the least possible friction between the parts.

10 Due to the engagement of the lugs 9 in the apertures 10, the carry iron is prevented 15 from slipping on the supporting ledges 4, as possibly might occur under certain conditions. Such slipping of the roller on the supports would result in its being displaced 20 to the limit of its movement, or until the side of the channel 7 were brought up against the bolt 8. In this displaced position, it will be seen the roller would be incapable of any further movement in the 25 same direction, and hence would cease to function as a roller-support. It will readily be seen how the interengagement of the roller and supports by virtue of the projections and apertures 9 and 10 obviates this 30 undesirable possibility, as this interengagement holds the roller against sliding movement on the supporting ledges, with the result that it is compelled to roll under all 35 conditions. Thus relative displacement of the roller and its supports is prevented, and they will always bear the proper relationship, depending, of course, upon the position of the draw bar.

40 These interengaging portions on the supports and roller have a further valuable function in that they provide means whereby the roller may be properly centered when it is inserted, as the registering of the interengaging portions places the selected bearing surface in proper position; furthermore, the construction maintains the roller in proper alignment with the supports.

45 A still further function of this construction is that of preventing the overturning 50 of the roller in case it is freed from pressure of the draw bar. It can be seen how, if unhindered, the roller would naturally assume the position with the high bearing face downward. When positioned with the high bearing face upward, the roller is prevented

55 from overturning by the interengaging portions in coöperation with the bolt 8, as when the roller reaches the limit of movement allowed by the bolt 8, the interengagement of the projections 9 and apertures 10 will prevent its further rotation.

60 I am aware that the device illustrated and described is capable of various modifications, and that my invention is susceptible of embodiment in forms other than that herein disclosed.

65 What I claim is:

1. A draw bar supporting device comprising a carry iron for supporting the draw bar, said carry iron being provided with 70 trunnions at its extremities, supports spaced apart longitudinally of the carry iron and providing supporting surfaces upon which said trunnions are disposed to rock, means associated with the supports and the carry 75 iron to limit the movement of the latter to prevent its disengagement from the former, each support and its associated trunnion being provided with interengaging portions whereby the carry iron is maintained in 80 proper alignment relative to the supports and held against sliding movement thereon.

2. A draw bar supporting device comprising a carry iron provided with terminal 85 trunnions, supporting members spaced apart longitudinally of the carry iron and affording supporting surfaces upon which said trunnions are disposed to rock, said carry iron including a portion extending eccentrically relative to the axis of the trunnions 90 and arranged for rocking coöperation with the draw bar, said supports and trunnions being provided with interengaging portions adapted to maintain the carry iron in alignment relative to the supports and to hold 95 said parts against relative sliding movement, and a retaining member adapted for engagement with the carry iron to limit its rocking movement on the supports, said retaining member coöperating with said interengaging portions to maintain the eccentric portion of the carry iron in operative position relative to the supports.

100 In testimony whereof I hereunto affix my signature in the presence of two witnesses, this 12th day of August, 1915.

CHARLES T. WESTLAKE.
